Primary Examiner — S. Bryan Reinholdt, Jr.*Assistant Examiner* — Kaitlan Walker(74) *Attorney, Agent, or Firm* — LADAS & PARRY LLP(57) **CLAIM**

The ornamental design for a 'W' linear shaped charge casing, as shown and described.

DESCRIPTION

FIG. 1 is a front elevational view showing our design for a 'W' linear shaped charge casing;

FIG. 2 is a rear elevational view thereof;

FIG. 3 is a top plan view thereof;

FIG. 4 a bottom plan view thereof;

FIG. 5 is a left side elevational view thereof, the right side elevational view being a mirror image of the left side view; and,

FIG. 6 is a perspective view thereof.

The 'W' linear shaped charge casing includes a symbolic break along the length drawn in broken lines. The broken lines and the area between the break lines form no part of the claimed design.
